UNITED STATES PATENT OFFICE.

LEVI H. MANNING, OF TUCSON, ARIZONA.

APPARATUS FOR TREATING HYDROCARBON OILS.

Application filed April 16, 1921. Serial No. 461,995.

To all whom it may concern:

Be it known that I, LEVI H. MANNING, a citizen of the United States, residing at Tucson, in the county of Pima and State of Arizona, have invented certain new and useful Improvements in Apparatus for Treating Hydrocarbon Oils, of which the following is a specification.

This invention relates to apparatus for 10 heat treating hydrocarbon oils to obtain different materials, and in particular, the apparatus relates to means for producing low boiling hydrocarbon oils from relatively high boiling petroleum oils.

15 The features of the invention include details of apparatus for cracking petroleum oil, by which means it is possible to treat liquid oil to obtain lighter products without the usual trouble resulting from carbon 20 deposits.

One particular feature provides for the treatment of liquid oil in such a way that carbon and heavy material is moved to points of relative quiet for removal, while the other 25 portions of a mass of liquid oil are subjected to a pulsating agitating movement within prescribed limits, as contrasted to a flowing movement, and at the same time that the portion undergoing agitation is subjected to 30 a heat treatment. This feature also provides that no heat shall be applied to the portions not undergoing agitation and to that part of the apparatus where the mass of oil is relatively quiet.

35 Details of the apparatus provide for the use of particular elliptically shaped discs or vanes mounted on a rotary shaft and arranged to revolve therewith within a tubular still which has a bore approximately that of 40 the shorter diameter of the vanes. These peculiarly shaped vanes and their mounting on the shaft make possible the pulsating movement of the oil and also provide for the agitating movement in situ of cleaner 45 members located between the vanes and propelled thereby.

The invention provides also for the continuous operation of the apparatus and any process which may be performed therein and 50 for the continuous introduction and withdrawal of material treated and produced.

The above and other features and details of the invention are described and claimed in the accompanying specification and claims

and illustrated in the accompanying drawings in which—

Figure 1 is a side elevation of the apparatus showing the relative position of the parts and indicating in dotted lines the 55 relation of the furnace structure and heating means to the other portions of the apparatus;

Figure 2 is an enlarged view of one of the retort tubes, partly broken away and partly in section, showing the mounting of the vanes within the cracking tube and between the downwardly projecting pipes for 60 the removal of solid material;

Figure 3 is an enlarged view of the side 65 of one of the elliptical agitator scraper vanes;

Figure 4 is a front view taken axially of the vane shown in Figure 3;

Figure 5 is a view of the rotatable shaft removed from one of the treatment tubes 70 and showing the splines which are adapted 75 to engage the keyway of the vanes; and

Figure 6 is a view of the vane shown in Figure 4 taken at right angles to the plane 80 of the vane, and showing the elliptical contour of the periphery of the vanes.

Like reference characters indicate like 85 parts in the various figures of the drawings.

Referring in detail to the construction illustrated in the drawings, 1 represents the masonry construction, either concrete, stone or brick, but preferably fire-brick, such as will stand severe temperatures. A suitable stack is provided for leading off the furnace fumes, smoke, and gases of combustion. A 90 source of heat is provided by burners, not shown, located at the lower part of the furnace and supplied with liquid fuel by pipes 3 communicating with the point of removal of waste oil from the apparatus, as will be described. Individual branch pipes 95 3^a are connected with the burner supply pipes 3 and are provided with independent valves 3^b for regulating the supply of burning oil to the burners. An additional valve 3^c is located in the pipe 3 and may be used 100 for regulating the use of either one of two burners and the connection between such burners and the branch pipes 3^a. The flame and hot gases from the burner nozzles is projected inwardly and passed upwardly in 105 the furnace to ultimately escape through the stack 2. During the upward movement, the heat comes into direct contact with the ex-

terior of a plurality of longitudinally positioned retort tubes, as will be described.

The drawing illustrates two cracking tubes or retort tubes 4 and 5, positioned one 6 above the other and substantially horizontally. The number of tubes might well be limited to one or increased to three or four, providing the heating arrangements and mechanical features could be satisfactorily operated. Within the tubes 4 and 5 are the combined agitator scraper vanes or discs 4^a and 5^a, mounted on and adapted to turn with their respective shafts 4^b and 5^b respectively. Suitable journal boxes or stuffing boxes are 10 indicated for the respective shafts at 4^c and 5^c. The details of the construction and shape of the vanes constitute an important feature of the present invention. Referring particularly to Figures 2, 3, 4 and 5, it will 15 be noted that each vane is mounted on the shaft at an angle to the shaft and that each substantially fills the bore of the cylindrical tube. Each vane is elliptical in shape and has substantially the same shape as that 20 of an inclined section taken through the cylindrical tube within which it is mounted. Thus in Figure 6 there is shown the exact relative dimensions of the vane, and in Figure 4 the longer dimension is shortened, be- 25 cause the view is taken axially instead of at right angles as in Figure 6. Each vane has a hub portion 4^e having right angle shoulders 4^f which are adapted to engage 30 corresponding shoulders on adjacent vanes 35 when the apparatus is in its assembled form. The shaft 4^b is provided with longitudinally extending splines 4^g adapted to engage the keyway slot or groove 4^h provided in the 40 axial opening of the vanes. Each vane is also provided with a plurality of perforations 4ⁱ through which oil may be forced 45 during the operation of the apparatus, as will be described.

Referring to Figures 1 and 2, 6 indicates 45 a communicating tube extending from the retort tube 4 to the retort tube 5 and located at the left side of the structure adjacent the ends of the tubes. A similar communicating tube 6^a is provided adjacent the opposite ends of the tube. It will 50 be observed that the agitating scraper vanes are not positioned opposite the communicating tubes 6 and 6^a. At the left hand end of the lower tube 5 is a draw off pipe 55 7 for removing carbon and relatively heavy material which may be formed during the operation of the apparatus. A similar draw off pipe 7^a is provided at the opposite end of the lower tube 5. Valves 8 and 8^a are 60 provided on the respective pipe 7 and 7^a. The operation provides for the use of the heavy material which is withdrawn for fuel in the burners beneath the apparatus and to this end a pipe 9 is connected to the pipes 65 7 and 7^a and conducts this fuel material to

the burner supply pipe 3 and its branch pipe 3^a. Valves 9^a are provided for regulating the admission of waste material from the pipes 7 and 7^a to the pipe 9.

At the top of the system of cracking tubes 70 and above the furnace 1 is positioned a large reservoir or expansion chamber 10 which communicates with the top of each end of the upper cracking tube 4 by means of the pipes 11 and 11^a leading from the lower side 75 and opposite ends of the chamber 10. A series of test drain pipes provided with suitable valves are indicated at 10^b at different elevations on the chamber to determine the height of oil therein and the nature of the oil at different heights. Additional means for determining the height of oil within the chamber is indicated at 10^b in which a float, shown in dotted lines, within the chamber 80 operates an indicating arrow on the outside of the chamber by means of a connecting lever. Oil is conducted from an oil tank or other suitable source of supply, not shown, through the pipe 12 to a pump 13 which is adapted to force the oil against the pressure within the apparatus upwardly through the pipe 14, past the valve 15^a and through the pipe 15 to the top of the expansion chamber 10, or directly into the 85 communicating pipe 6 by being led into the pipe 16 past the valve 16^a. Operation of the valves 15^a and 16^a will regulate the point and volume of the flow of untreated fresh oil through either one or both of the pipes 15 and 16 respectively. Immediately above 90 the expansion chamber 10 are the upwardly extending vapor removing pipes 17, 17^a and 17^b which are connected to the pipe 18 by means of a regulating valve 18^a, and all materials in an aeriform condition are led 95 through the pipe 18 to a condenser, not shown. An additional pipe connection is indicated at 19 on the upper side of the expansion chamber 10 and may serve to connect the apparatus to any suitable reflux 100 condenser, not shown.

Drive means for driving the shafts 4^b and 5^b is provided by a main drive belt 20 connected to any suitable source of power, not shown, and which passes over a pulley wheel 21 which is mounted to turn a shaft 22. A bevel gear 23 is mounted to rotate with the shaft 22 and is in mesh with a similar larger bevel gear 24 mounted on a shaft 25 which latter is illustrated as substantially parallel to the retort tubes 4 and 5. A gear 26 is fixed to turn with the shaft 25 and is in mesh with the gears 4^d and 5^d which are respectively fixed to rotate with the shafts 4^b and 5^b.

Within the retort tubes and positioned between the parallel blades of the combined agitator and scraper vanes are metal balls 27 which remain in the retort tubes in their respective positions between the vanes and

are moved back and forth in these fixed restricted locations during the rotation of the vanes. Thus the balls have a movement in situ and are free to roll and tumble within 5 prescribed limits, namely between adjacent vanes.

In the revolution of the shafts 4^b and 5^b the movement of the vanes performs a function which is peculiar to the present invention. Referring particularly to the view in Figure 2, it will be noted that the space between A and D is scraped by the vane connected by lines from these letters. Likewise, it will be noted that the lines from the 10 letters B and D dropped from the extreme upper tips of the vanes which are adjacent pass through substantially the center point of the vane next to the right, and that a line taken upwardly as from C from the lower 15 tip of one vane is spaced slightly from the line taken from B and does not touch the upper tip of the second vane to the left, but barely misses the second vane. In a single revolution of the shaft 4^b or 5^b with its 20 vanes that portion of the wall of the cylindrical cracking tubes is scraped four times within the space between the lines A—B and C—D, and the portion between the lines B and C and the portion opposite the 25 extreme tip of the vanes is scraped twice. This is made possible because of the inclined position of the vanes, their close parallel relation, and their particular elliptical shape. This multiple scraping action 30 may be understood better by observing that the portions between A and B and between C and D is engaged once by each of the two sides of the vane, as for instance the points X and Y on the vane shown in Figure 6, 35 and also by the corresponding points on the lower end of the vane next to the right, which latter points will underlie or be opposite to the points X and Y, when X and Y are located in any position or at the top as 40 shown in Figure 2.

The operation of the movement of oil into and out of the apparatus, and the treatment of the fresh material within the retort cylinder tubes may be understood from the following description. Oil is introduced 45 through the pipes 15 or 16 in sufficient quantity to have the retort tube in the furnace preferably full of oil, and preferably the oil is in sufficient quantity to substantially half fill the expansion chamber 10, which latter also serves as a reservoir. During the operation of the apparatus and the process which would be performed thereby, oil flows downward through the pipes 11 50 and 11^a and into the treatment tubes 4 and 5. The revolution of the agitating scraper vanes causes a pulsating movement of the oil back and forth and is to be contrasted to a conveyor action. It will be noted that 55 the ends of the retort tubes are not provided

with agitator scraper vanes and that these vanes do not extend over the openings of pipes 6 and 6^a, and 7 and 7^a, but are positioned between such points. There is, therefore, a region of relative quiet in the oil at 70 these points such as will permit the settling out of carbon and relatively heavy material formed during the retort and cracking treatment. At the same time it has been found that the agitation of the oil 75 during the revolution of the vanes serves to keep any carbon formed in suspension in the oil, and to pass such relatively solid material to points of relative quiet, that is to the ends of the tubes and to points adjacent 80 the withdrawal pipes 6 and 6^a, and 7 and 7^a, down through which pipe openings the carbon and solid material is permitted to gravitate to ultimately be withdrawn for use as fuel in the apparatus or for other treatment. 85 It will be observed that the operation provides an unusually efficient scraping apparatus without requiring any conveying action of the oil through the treatment tubes, and this combined agitation and scraping 90 movement is believed to be one explanation of the unusually satisfactory results which the apparatus has made possible. The openings in the agitator scraper vanes permit the escape of portions of the oil endwise in the tubes, and this may explain the performance by which the carbon is permitted to settle at the points of relative quiet at the ends of the tubes. The presence 95 of the balls, preferably steel balls, 27 assists in cutting carbon formations from the interior of the cylinder walls and also from the surface of the agitator scraper vanes. The combined action of the agitator is thus 100 to scrape the interior of the tube walls and also to serve the function of keeping the carbon and heavy material in suspension until it reaches the points of rest and relative quiet in the region of the outlet pipes. 105

The continuous operation provides for the 110 constant removal of aeriform material from the upper side of the expansion chamber and discharge of such material through the pipe 18 to a condenser, and during this movement a continuous withdrawal of carbon and heavy material which constantly settles in the region of quiet above the ends of the withdrawal pipes 7 and 7^a. The rate 115 of withdrawal of aeriform material and of waste material, and the rate of introduction of heat treated oil is dependent on the size of the apparatus and the relative production as result of a particular temperature treatment, pressure and atmospheric conditions. The valves governing the inlet 120 and outlet pipes may therefore be adjusted to suit such conditions.

The apparatus and the process have been satisfactorily operated in a plant having retort tubes ten feet long and having a six 125 130

inch bore, arranged substantially as illustrated. The vanes substantially filled this bore and had a close fitting engagement with the tube walls which was sufficient to 5 provide a positive scraping action, but not sufficient to bind the vanes and hinder the revolution of the shaft. The invention provides for cranking and the production of light materials from relatively heavy, and 10 has operated satisfactorily at temperatures ranging from 700° F. upward in treating California oils of various qualities. By providing for the application of heat to those portions only where there was a scraping and agitating action it has been possible 15 to permit the settling action of the relatively heavy material without incurring carbon formation in the region of such settling.

20 The process which relates to the peculiar agitating pulsating movement and to the method of separating out the carbon and heavy material, and the details of the cracking operation are set forth in my co-pending 25 application Serial No. 461,994.

I claim:

1. In an apparatus for heat treating hydrocarbon oils, a cylindrical treatment chamber, means for heating the exterior of said 30 chamber, a rotatable shaft extending centrally through the length of said chamber, and a series of vanes fixed on said shaft to rotate therewith, each vane having its broader face transverse to the axis of said 35 shaft and being positioned at an inclined angle to the axis of said shaft.

2. In an apparatus for heat treating hydrocarbon oils, a cylindrical treatment chamber, means for heating the exterior of said 40 chamber, a rotatable shaft extending centrally through the length of said chamber, and a series of vanes fixed on said shaft to rotate therewith, each vane being positioned 45 at an inclined angle to the axis of said shaft and extending across substantially all the bore of said chamber.

3. In an apparatus for heat treating hydrocarbon oils, a cylindrical treatment chamber, means for heating the exterior of said 50 chamber, a rotatable shaft extending centrally through the length of said chamber, and a series of vanes fixed on said shaft to rotate therewith, each vane being elliptical in shape and inclined to said shaft.

55 4. In an apparatus for heat treating hydrocarbon oils, a cylindrical treatment chamber, means for heating the exterior of said chamber, a rotatable shaft extending centrally through the length of said chamber, 60 and a series of parallel vanes spaced apart and fixed on said shaft to rotate therewith, each vane being elliptical in shape and inclined to said shaft.

65 5. In an apparatus for heat treating hydrocarbon oils, a cylindrical treatment cham-

ber, means for heating the exterior of said chamber, a rotatable shaft extending centrally through the length of said chamber, and a series of combined agitating and scraping vanes fixed on said shaft to rotate therewith, each vane being positioned at an inclined angle to the axis of said shaft and extending across substantially all the bore of said chamber.

6. In an apparatus for heat treating hydrocarbon oils, a cylindrical treatment chamber, means for heating the exterior of said chamber, a rotatable shaft extending centrally through the length of said chamber, and a series of combined agitating and scraping vanes fixed on said shaft to rotate therewith, each vane being elliptical in shape and inclined to said shaft.

7. In an apparatus for heat treating hydrocarbon oils, a cylindrical treatment chamber, means for heating the exterior of said chamber, a rotatable shaft extending centrally through the length of said chamber, and a series of combined agitating and scraping means fixed on said shaft to rotate therewith, said vanes being spaced apart and each being elliptical in shape and inclined to said shaft.

8. In an apparatus for heat treating hydrocarbon oils, a cylindrical chamber, an elliptically shaped agitating vane, inclined to the axis of said chamber, and on the interior of said chamber, said vane and said chamber being rotatable with respect to each other, and means for applying heat directly to the exterior of said chamber.

9. In an apparatus for heat treating hydrocarbon oils, a cylindrical chamber, an elliptically shaped agitating vane in the interior of said chamber and mounted to rotate on an axis inclined to the plane of the vane, and means for applying heat directly to the exterior of said chamber.

10. In an apparatus for heat treating hydrocarbon oils, a cylindrical treatment chamber, a rotatable shaft extending centrally through the length of said chamber, and a series of parallel elliptically shaped vanes fixed on said shaft to rotate therewith, each vane being positioned at such an angle to said shaft that a line taken from the extreme end of each vane at right angles to said shaft would intersect the next adjacent vane.

11. In an apparatus for treating hydrocarbon oils, a cylindrical treatment chamber, a rotatable shaft extending centrally through the length of said chamber, and a series of parallel elliptically shaped vanes fixed on said shaft to rotate therewith, each vane being positioned at such an angle to said shaft that a line taken from the extreme end of each vane at right angles to said shaft would intersect the next adjacent vane at about the axis thereof.

12. In an apparatus for treating hydro-carbon oils, a cylindrical treatment chamber, a rotatable shaft extending centrally through the length of said chamber, and a series of parallel elliptically shaped combined agitating and scraping vanes fixed on said shaft to rotate therewith, each vane being positioned at such an angle to said shaft that a line taken from the extreme end of each vane 5 at right angles to said shaft would intersect the next adjacent vane.
13. In an apparatus for treating hydro-carbon oils, a cylindrical treatment chamber, a rotatable shaft extending centrally through the length of said chamber, and a series of parallel elliptically shaped combined agitating and scraping vanes fixed on said shaft to rotate therewith, each vane being positioned at such an angle to said shaft that a line taken from the extreme end of each vane 10 at right angles to said shaft would intersect the next adjacent vane at about the axis thereof.
14. In an apparatus for treating hydro-carbon oils, a cylindrical treatment chamber, a rotatable shaft extending centrally through the length of said chamber, a series of parallel elliptically shaped combined agitating and scraping vanes fixed on said shaft to rotate therewith, each vane being positioned at such an angle to said shaft that a line taken from the extreme end of each vane 15 at right angles to said shaft would intersect the next adjacent vane, and means to heat said chamber by heat applied to the exterior of said chamber walls.
15. In an apparatus for treating hydro-carbon oils, a cylindrical treatment chamber, a rotatable shaft extending centrally through the length of said chamber, a series of parallel elliptically shaped combined agitating and scraping vanes fixed on said shaft to rotate therewith, each vane being positioned at such an angle to said shaft that a line taken from the extreme end of each vane 20 at right angles to said shaft would intersect the next adjacent vane at about the axis thereof, and means to heat said chamber by heat applied to the exterior of said chamber walls.
16. In an apparatus for treating hydro-carbon oils, a cylindrical treatment chamber, a rotatable shaft extending centrally through the length of said chamber, a series of vanes fixed on said shaft to rotate therewith, each vane being positioned at an inclined angle to the axis of said shaft, and a freely movable cleaner element positioned 25 between adjacent members of said series of vanes and adapted to move in situ during the movement of said shaft.
17. In an apparatus for treating hydro-carbon oils, a cylindrical treatment chamber, a rotatable shaft extending centrally through the length of said chamber, a series of combined agitating and scraping vanes fixed on said shaft to rotate therewith, each vane being elliptical in shape and inclined to said shaft, and a freely movable cleaner element positioned 30 between adjacent members of said series of vanes and adapted to move in situ during the movement of said shaft.
18. In an apparatus for treating hydro-carbon oils, a cylindrical treatment chamber, a rotatable shaft extending centrally through the length of said chamber, a series of vanes fixed on said shaft to rotate therewith, each vane being elliptical in shape inclined to said shaft, and a freely movable cleaner element positioned between adjacent members of said series of vanes and adapted to move in situ during the movement of said shaft.
19. In an apparatus for treating hydro-carbon oils, a cylindrical treatment chamber, a rotatable shaft extending centrally through the length of said chamber, a series of parallel vanes spaced apart and fixed on said shaft to rotate therewith, each vane being elliptical in shape inclined to said shaft, and a freely movable cleaner element positioned between adjacent members of said series of vanes and adapted to move in situ during the movement of said shaft.
20. In an apparatus for treating hydro-carbon oils, a cylindrical treatment chamber, a rotatable shaft extending centrally through the length of said chamber, a series of combined agitating and scraping vanes fixed on said shaft to rotate therewith, each vane being positioned at an inclined angle to the axis of said shaft and extending across substantially all the bore of said chamber, and a freely movable metal ball cleaner element positioned between adjacent members of said series of vanes and adapted to move in situ during the movement of said shaft.
21. In an apparatus for treating hydro-carbon oils, a cylindrical treatment chamber, a rotatable shaft extending centrally through the length of said chamber, a series of combined agitating and scraping vanes fixed on said shaft to rotate therewith, each vane being elliptical in shape and inclined to said shaft, and a freely movable metal ball cleaner element positioned between adjacent members of said series of vanes and adapted to move in situ during the movement of said shaft.
22. In an apparatus for treating hydro-carbon oils, a cylindrical treatment chamber, a rotatable shaft extending centrally through the length of said chamber, a series of combined agitating and scraping vanes fixed on said shaft to rotate therewith, said vanes being spaced apart and each being elliptical in shape and inclined to said

shaft, and a freely movable metal ball cleaner element positioned between adjacent members of said series of vanes and adapted to move in situ during the movement of said shaft.

23. In an apparatus for treating hydro-carbon oils, a cylindrical treatment chamber, a rotatable shaft extending centrally through the length of said chamber, a series of parallel elliptically shaped vanes fixed on said shaft to rotate therewith, each vane being positioned at such an angle to said shaft that a line taken from the extreme end of each vane at right angles to said shaft would intersect the next adjacent vane, and a freely movable cleaner element positioned between adjacent members of said series of vanes and adapted to move in situ during the movement of said shaft.

24. In an apparatus for treating hydro-carbon oils, a cylindrical treatment chamber, a rotatable shaft extending centrally through the length of said chamber, a series of parallel elliptically shaped vanes fixed on said shaft to rotate therewith, each vane being positioned at such an angle to said shaft that a line taken from the extreme end of each vane at right angles to said shaft would intersect the next adjacent vane at about the axis thereof, and a freely movable cleaner element positioned between adjacent members of said series of vanes and adapted to move in situ during the movement of said shaft.

25. In an apparatus for treating hydro-carbon oils, a cylindrical treatment chamber, a rotatable shaft extending centrally through the length of said chamber, a series of parallel elliptically shaped combined agitating and scraping vanes fixed on said shaft to rotate therewith, each vane being positioned at such an angle to said shaft that a line taken from the extreme end of each vane at right angles to said shaft would intersect the next adjacent vane, and a freely movable cleaner element positioned between adjacent members of said series of vanes and adapted to move in situ during the movement of said shaft.

26. In an apparatus for treating hydro-carbon oils, a cylindrical treatment chamber, a rotatable shaft extending centrally through the length of said chamber, a series of parallel elliptically shaped combined agitating and scraping vanes fixed on said shaft to rotate therewith, each vane being positioned at such an angle to said shaft that a line taken from the extreme end of each vane at right angles to said shaft would intersect the next adjacent vane at about the axis thereof, and a freely movable cleaner element positioned between adjacent members of said series of vanes and adapted to move in situ during the movement of said shaft.

27. In an apparatus for treating hydro-

carbon oils, a cylindrical treatment chamber, a rotatable shaft extending centrally through the length of said chamber, a series of combined agitating and scraping vanes fixed on said shaft to rotate therewith, each vane being positioned at an inclined angle to the axis of said shaft and extending across substantially all the bore of said chamber, means to heat said chamber by heat applied to the exterior of said chamber walls, and a freely movable metal ball cleaner element positioned between adjacent members of said series of vanes and adapted to move in situ during the movement of said shaft.

28. In an apparatus for treating hydro-carbon oils, a cylindrical treatment chamber, a rotatable shaft extending centrally through the length of said chamber, a series of combined agitating and scraping vanes fixed on said shaft to rotate therewith, each vane being elliptical in shape and inclined to said shaft, means to heat said chamber by heat applied to the exterior of said chamber walls, and a freely movable metal ball cleaner element positioned between adjacent members of said series of vanes and adapted to move in situ during the movement of said shaft.

29. In an apparatus for treating hydro-carbon oils, a cylindrical treatment chamber, a rotatable shaft extending centrally through the length of said chamber, a series of combined agitating and scraping means fixed on said shaft to rotate therewith, said vanes being spaced apart and each being elliptical in shape and inclined to said shaft, means to heat said chamber by heat applied to the exterior of said chamber walls, and a freely movable metal ball cleaner element positioned between adjacent members of said series of vanes and adapted to move in situ during the movement of said shaft.

30. In an apparatus for treating hydro-carbon oils, a cylindrical treatment chamber, a rotatable shaft extending centrally through the length of said chamber, a series of parallel elliptically shaped combined agitating and scraping vanes fixed on said shaft to rotate therewith, each vane being positioned at such an angle to said shaft that a line taken from the extreme end of each vane at right angles to said shaft would intersect the next adjacent vane, means to heat said chamber by heat applied to the exterior of said chamber walls, and a freely movable metal ball cleaner element positioned between adjacent members of said series of vanes and adapted to move in situ during the movement of said shaft.

31. In an apparatus for treating hydro-carbon oils, a cylindrical treatment chamber, a rotatable shaft extending centrally through the length of said chamber, a series of parallel elliptically shaped combined agitating and scraping vanes fixed on said shaft to rotate therewith, each vane being positioned

- at such an angle to said shaft that a line taken from the extreme end of each vane at right angles to said shaft would intersect the next adjacent vane at about the axis thereof, means to heat said chamber by heat applied to the exterior of said chamber walls, and a freely movable metal ball cleaner element positioned between adjacent members of said series of vanes and adapted to move in situ during the movement of said shaft.
32. In an apparatus for heat treating hydrocarbon oils, a tubular treatment chamber, means for heating the exterior of said chamber, and a movable elliptically shaped perforate agitating vane within said chamber, inclined to the longitudinal center thereof, and having all of its periphery in scraping position adjacent the inner wall of said chamber.
33. In an apparatus for heat treating hydrocarbon oils, a treatment chamber having a wall adapted to be heated, means for heating the wall of said chamber, and an elliptically shaped perforate agitating vane mounted to rotate on an axis inclined to the plane of the vane and having all of its periphery positioned directly adjacent and in position for scraping the interior of the heated portion of the wall of said chamber.
34. In an apparatus for treating hydrocarbon oils, a laterally extending elongated treatment chamber having an intake opening, and an outlet pipe opening in its lower side adjacent one end of said chamber and a second outlet pipe opening adjacent the opposite end, and an agitator member within said chamber and positioned between and not opposite said outlet openings, said agitator member comprising means to effect an endwise pulsating movement of the oil material within said chamber.
35. In an apparatus for treating hydrocarbon oils, a laterally extending elongated treatment chamber having an intake opening, and an outlet pipe opening in its lower side adjacent one end of said chamber and a second outlet pipe opening adjacent the opposite end, a combined agitator and scraper member within said chamber and positioned between and not opposite said outlet openings, said agitator member comprising means to effect an endwise pulsating movement of the oil material within said chamber, and heating means for heating the chamber opposite the agitator and scraper member.
36. In an apparatus for treating hydrocarbon oils, a laterally extending cylindrical treatment chamber having an intake opening, and an outlet pipe opening in its lower side, a rotatable shaft extending centrally through the length of said chamber, and agitator means mounted on said shaft and adapted to rotate therewith and spaced
- from said outlet opening, said shaft and agitator means together comprising means for providing an endwise pulsating movement of the oil undergoing treatment.
37. In an apparatus for treating hydrocarbon oils, a laterally extending cylindrical treatment chamber having an intake opening, and a plurality of outlet openings in its lower side, a rotatable shaft extending centrally through the length of said chamber, and agitator means mounted on said shaft and adapted to rotate therewith and positioned between said outlet openings, said shaft and agitator means together comprising means for providing an endwise pulsating movement of the oil undergoing treatment.
38. In an apparatus for treating hydrocarbon oils, a laterally extending cylindrical treatment chamber having an intake opening, and an outlet pipe opening in its lower side, a rotatable shaft extending centrally through the length of said chamber, and a series of elliptically shaped agitating vanes fixed on said shaft and adapted to rotate therewith, said vanes being positioned to one side of but not opposite said outlet opening, said shaft and vanes together constituting means for providing an endwise pulsating movement of the oil undergoing treatment.
39. In an apparatus for treating hydrocarbon oils, a laterally extending cylindrical treatment chamber having an intake opening, and a plurality of outlet openings in its lower side, a rotatable shaft extending centrally through the length of said chamber, and a series of elliptically shaped agitating vanes fixed on said shaft and adapted to rotate therewith, said vanes being positioned between but not opposite said outlet openings, said shaft and vanes together constituting means for providing an endwise pulsating movement of the oil undergoing treatment.
40. In an apparatus for treating hydrocarbon oils, a laterally extending cylindrical treatment chamber having an intake opening, and an outlet pipe opening in its lower side, a rotatable shaft extending centrally through the length of said chamber, a series of elliptically shaped agitating and scraping vanes fixed on said shaft, the periphery of each vane being in constant fixed close relation to the inner wall of said chamber, and heating means for heating said chamber and its contents by heat applied to the exterior of said chamber, said vanes and said heating means being located in spaced relation from said outlet opening, said shaft and vanes together constituting means for providing an endwise pulsating movement of the oil undergoing treatment.
41. In an apparatus for treating hydro-

carbon oils, a laterally extending cylindrical treatment chamber having an intake opening, and a plurality of outlet openings in its lower side, a rotatable shaft extending centrally through the length of said chamber, a series of elliptically shaped agitating and scraping vanes fixed on said shaft, the periphery of each vane being in constant fixed close relation to the inner wall of said chamber, and heating means for heating said chamber and its contents by heat applied to the exterior of said chamber, said vanes and said heating means being located between said outlet openings and not opposite said openings, said shaft and vanes together constituting means for providing an endwise pulsating movement of the oil undergoing treatment.

42. In an apparatus for treating hydrocarbon oils, a laterally extending cylindrical treatment chamber having an intake opening, and an outlet pipe opening in its lower side, a rotatable shaft extending centrally through the length of said chamber, a series of elliptically shaped agitating and scraping vanes fixed on said shaft, the periphery of each vane being in constant fixed close relation to the inner wall of said chamber, and heating means for heating said chamber and its contents by heat applied to the exterior of said chamber, said vanes and said heating means being opposite to each other and both being spaced from said outlet opening, said shaft and vanes together constituting means for providing an endwise pulsating movement of the oil undergoing treatment.

43. In an apparatus for treating hydrocarbon oils, a laterally extending cylindrical treatment chamber having an intake opening, and a plurality of outlet openings in its lower side, a rotatable shaft extending centrally through the length of said chamber, a series of elliptically shaped agitating and scraping vanes fixed on said shaft, the periphery of each vane being in constant fixed close relation to the inner wall of said chamber, and heating means for heating said chamber and its contents by heat applied to the exterior of said chamber, said vanes and said heating means being opposite each other and both being located between said outlet openings and not opposite said openings, said shaft and vanes together constituting means for providing an endwise pulsating movement of the oil undergoing treatment.

44. Apparatus for treating hydrocarbon materials comprising a tubular treatment chamber, means for heating said chamber, a plurality of cleaner elements in said chamber freely movable in situ therein, and conveyer means within said tubular chamber for moving said cleaner elements in situ therein, said cleaner elements being moved

within said chamber but free to roll or tumble therein.

45. Apparatus for treating hydrocarbon materials comprising a tubular treatment chamber, means for heating said chamber, a plurality of metal ball cleaner elements in said chamber freely movable in situ therein, and conveyer means within said chamber for moving said cleaner elements in situ in said chamber.

46. Apparatus for treating hydrocarbon materials comprising a tubular treatment chamber, means for heating said chamber, a plurality of metal ball cleaner elements in said chamber and freely movable in situ therein, and a rotary conveyer member within said tubular chamber for moving said metal ball cleaner elements in situ lengthwise of said chamber.

47. Apparatus for treating liquids comprising a tubular casing, agitator means within said casing, said agitator means constituting means for providing an endwise pulsating movement of the material undergoing treatment, and means for heating the exterior of said casing at a point opposite said agitator means.

48. Apparatus for treating liquids comprising a tubular casing, agitator means within said casing including plate means having its edges so closely adjacent to the inner walls of the inner casing as to substantially prevent the passage between said plate means and said casing of material undergoing treatment, means for moving said plate means to effect an endwise pulsating movement of the material undergoing treatment, and means for heating the exterior of said casing at a point opposite said agitator means.

49. Apparatus for treating liquids comprising a tubular casing, agitator means within said casing positioned for preventing travel of material undergoing treatment between said agitator means and said casing wall, said agitator means constituting means for providing an endwise pulsating movement of the material undergoing treatment, and means for heating the exterior of said casing at a point opposite said agitator means.

50. In apparatus for treating liquid comprising a tubular casing, a plurality of vanes spaced apart and rotatably mounted in said casing, a freely movable cleaner element between adjacent vanes, and actuating means for rotatably moving said vanes, said actuating means and vanes together constituting combined means for moving said cleaner element lengthwise of said chamber within prescribed limits therein.

In testimony whereof I affix my signature. LEVI H. MANNING.
